UNITED STATES PATENT OFFICE.

ERNEST F. ELMBERG, OF CHICAGO, ILLINOIS.

DESIGN FOR A PUZZLE-BOX.

SPECIFICATION forming part of Design No. 28,205, dated January 18, 1898.

Application filed December 13, 1897. Serial No. 661,749. Term of patent 3½ years.

To all whom it may concern:

Be it known that I, ERNEST F. ELMBERG, of Chicago, in the county of Cook and State of Illinois, have invented and produced a new and original Design for a Puzzle-Box, of which the following is a full, clear, and exact description.

The design relates to puzzle-boxes having partitions forming irregular mazes, and the leading features will be hereinafter pointed out.

Reference is to be had to the accompanying drawings, forming a part of this specification, in which—

15 Figure 1 is a plan view of a puzzle-box embodying my new design, and Fig. 2 is a vertical section on line 2 2 of Fig. 1.

The leading feature of the design consists of the rectangular base A, with partitions of 20 the peculiar form and disposition shown, to wit: A border B B' B² B³ rises from the base at the edge. In one angle of the box are a series of curved spaced partitions c c' c² c³, one end c⁵ of the outermost partition being 25 extended into the angle formed by the side B' B² of the box, the next partition c' having one end returned to provide a three-sided inclosure, which is also covered, as at c⁶, while the opposite end c⁷ of partition c' extends 30 inward at an angle toward the center of the box. The next partitions c² c³ are joined at one end to close the intervening passage, as at c⁴, and at the opposite ends the partition c² terminates short of the angular terminal c⁷, 35 while the partition c³ has an extension c⁸, which joins c⁷ at the end of the latter, and from the point where c⁷ and c⁸ join the latter is curved, as at c⁹, and extends laterally and terminates short of one side B² of the box.

40 Within the partial inclosure formed by the members c⁵ c⁷ c⁹ is an isolated partition c¹⁰, forming a space closed except for an opening at one side, the partition having at one end sides flaring like the diverging sides of a 45 trapezoid and being at the other end in the form of two sides of a triangle. A partition b extends from partition c³ at about equal

distances from the sides of the box and joins with a transversely irregular ranging partition d, from one end of which departs a 50 slightly curved member d', while from the opposite end of partition d departs at almost a right angle the member d², the latter again being curved toward and joining one arm of an L-shaped partition d³. From the side B² 55 of the box parallel with the longer arm of partition d³ departs a partition e, the angle formed by the partition e and the side B² being covered as at e', and the front e² of the closed angle being curved. From the partition d at about the center starts a partition f, which terminates about on a line with the partition e, then turns at right angles to extend about in line with the said main length of partition e, as at f', its end terminating in 60 a curvature, as at f². Parallel with the partition f is a partition h, which joins at one end with the transverse member f', and at the opposite end terminates short of the partition d. A partition i ranges parallel with 65 the partition e and terminates at one end short of the side B². A short partition f³ joins partitions f and i. In the angle formed by the sides B' B² is a diagonal partition j. Adjacent to the diagonal partition j a partition k departs from the side B³, then turns at 70 right angles toward the side B², and terminates in an angular return-bend k'. From the junction of partitions i and f³ departs a partition i', which starts in a curve, then 75 ranges parallel with the side B³, as at i², and terminates short of the adjacent side B, and from the end of the member i² there departs a short straight member l, which terminates in a long compound curve, as at l'. The 80 space between the curved partitions c and the sides B B³ is covered, as at m.

I claim—

The design for a puzzle-box herein shown and described.

ERNEST F. ELMBERG.
